UNITED STATES PATENT OFFICE.

DAVID STENHOUSE, OF CLARKSBURG, WEST VIRGINIA.

LEER FOR ANNEALING GLASSWARE.

Application filed September 30, 1920. Serial No. 413,691.

To all whom it may concern:

Be it known that I, DAVID STENHOUSE, a citizen of the United States of America, and resident of Clarksburg, county of Harrison, and State of West Virginia, have invented certain new and useful Improvements in Leers for Annealing Glassware, of which the following is a specification.

This invention relates broadly to annealing furnaces, and more particularly to a leer for the annealing of glassware.

The primary object of the invention is to provide a leer in which a natural seal is created in the portion thereof which carries the maximum temperature, thereby obviating the necessity for employing doors or other heat-confining means.

A further object is to provide a leer in which proper annealing of the ware may be accomplished in a practical and efficient manner in a small fraction of the time required by prior leer structures.

A still further object is to provide a leer in which, during the return of the conveyor or ware-carrying medium to the charging point, said conveyor is preheated to a temperature approximating the charging temperature of the ware, largely utilizing for this purpose waste heat given up by the ware and the advancing portion of the conveyor in passing to and through the cooling chamber of the leer, the purpose being not only to prepare said conveyor for the reception of the ware which is to be annealed and eliminate the danger of fracture which exists when the temperature of such conveyor is materially lower than the charging temperature of the ware, but also to effect the preheating without material increase in fuel consumption, or by means of reclaimed heat.

Another object is to provide a leer which may have its charging end located closely adjacent to the ware-forming machine or machines without materially reducing or interfering with factory floor space, permitting the employment of carrying-in boys and leer feeding devices heretofore required to be wholly dispensed with.

A still further object within the contemplation of the invention is to provide, in a leer of the character mentioned, an improved and novel form of conveyor whereby the ware is carried through the leer.

With these and other important objects in view, the invention resides in the features of construction, arrangement of parts and

combinations of elements which will herein-after be fully described, reference being had to the accompanying drawings, in which—

Figure 1 is a longitudinal section of the invention, illustrating the features thereof in a more or less diagrammatic manner;

Figure 2 is an enlarged transverse section on line 2—2, Fig. 1;

Figure 3 is an enlarged top plan view of one of the ware carriers;

Figure 4 is sectional end elevation in which the section is taken on the line 4—4, Fig. 3, showing the track-ways for the traveling chains; and—

Figure 5 is an enlarged detail view in side elevation of a fragmentary portion of the conveyor.

Referring to said drawings, in which like designating characters distinguish like parts throughout the several views—

1 indicates a furnace or main annealing chamber forming a part of the leer, said chamber being located at a high elevation and being suitably supported, as by a structural steel supporting frame 2. Leading upward into the rear end of said chamber 1 is a passage 3 having located adjacent to its lower end an opening 4 through which glassware for annealing is introduced, and leading downward from the front end of said chamber is a passage 5. Said passages 3 and 5 constitute, respectively, ascending and descending legs through which the ware is transported in passing to and from said chamber 1. The descending leg 5 communicates at its lower end with the rear end of a long passage or chamber 6, hereinafter termed the cooling chamber, in which during its passage the ware is gradually reduced in temperature following heating thereof to the required high temperature in the furnace chamber 1.

Beneath the floor of the furnace chamber 1, which may be heated electrically or by any other suitable heating means, is a passage 8 which communicates at its rear and front ends, respectively, with vertical passages 9 and 10 located adjacent to and separated from the ascending and descending legs 3 and 5, respectively, by partitions 11 and 12 which extend downward from the opposite ends of said floor 7 to points adjacent to the lower ends of said legs.

Arranged within the leer is an endless traveling conveyor comprising a pair of sprocket chains 15 of that type which em-

bodies carrying rollers 14 adapted for travel upon trackways, as 13. Said chains are carried by a plurality of sets of sprocket wheels 16 disposed at points for causing travel of said chains throughout a path or course substantially as follows: From a point at or adjacent to the lower end of the ascending leg 3 of the leer upward through said leg to the rear end of the furnace chamber 1, thence horizontally through said chamber, thence downward through the descending leg 5 to the upper part of the adjacent end of the cooling chamber 6, thence forward on a slight downward incline through said cooling chamber, thence back through said cooling chamber beneath the therein-advancing portion of the conveyor, thence upward through the passage 10 to the front end of passage 8, thence rearward to the passage 9, and thence downward through the latter to the point of beginning.

The carrying sprockets 16 of each set have a relatively staggered arrangement, as shown, so that one of the chains 15 carried thereby is at all times disposed somewhat in advance of the other, providing for the mounting of ware-supporting pans or trays 17 on said chains in such manner that the same are at all times held in horizontal ware-carrying position. As shown, said pans or trays are seated upon arms 18 formed upon or carried by a shaft or bar 19 which has its opposite ends loosely mounted in bearings, as 20, formed upon the opposite chains at points which at all times occupy a common plane, or at points in which, in the horizontal positions of said chains, one is advanced beyond the other a distance corresponding to that at which one sprocket 16 of each set is advanced with respect to the other; and the intermediate or body portion of said bar 19 is shaped to permit of the mounting of its ends in the relation described, as shown in Fig. 3.

45 Due to the relatively great elevation of the furnace chamber 1, a natural seal is created in the legs 3 and 5 for confining to said chamber the heat developed in the latter. Thus, it is possible to dispense with doors and other mechanical means commonly employed in leers for preventing the escape of heat and for preventing access of cold air.

Ware placed upon the trays 17 as the latter pass by the charging opening 4 is promptly elevated into the furnace chamber and is rapidly heated to the high temperature carried in the latter. During its passage through said chamber the ware is subjected to the required annealing heat, and in its descent through the descending leg 5 and its passage through the cooling chamber 6 the temperature of said ware is gradually reduced. Said cooling chamber may be provided throughout its length or any

desired portion thereof with suitable flues, as 21, preferably having thermostatic control, whereby the controlled escape of heat may be permitted. To provide for still more rapid cooling, cold air flues, as 22, opening upward through the floor of the cooling chamber may be arranged at suitable intervals.

As is obvious, since the return travel of the trays 17 to the charging point is in close proximity to the path of travel of the heated ware, said trays absorb heat given off by said ware and the furnace walls and floor, which heat would otherwise be wholly lost, so that at the charging point they possess a temperature approximating that of the ware which is delivered thereto from the ware-forming machines. This preheating of the conveyor by reclaimed heat results in a material economy in fuel consumption, it being understood that in prior structures it has been necessary to provide special means for heating the carriers or conveyors to a point at which the danger of fracture of articles of ware deposited thereon is reduced.

The leer is preferably so located that the ascending leg 3 thereof is closely adjacent to the ware-forming machines, so as to facilitate the transfer of the ware. Due to this arrangement and to the location of the furnace chamber at a considerable elevation above the factory floor so as to afford ample head room for the workmen, the described leer structure may be employed without material reduction in the floor space at points where such space is required for other purposes.

What is claimed is—

1. A leer for glassware, comprising a horizontally disposed main annealing chamber of substantial length, said chamber having ascending and descending legs communicating with its opposite ends and being located at a relatively great elevation whereby is created a natural seal for confining heat thereto, the ascending leg having a charging opening therein adjacent to its lower end, and an approximately horizontal cooling chamber communicating with said descending leg, and an endless ware conveyor arranged for advance travel from the charging opening to and through said cooling chamber and for return travel throughout a path in which its temperature is raised to the required point by absorption of heat given off by the ware and the leer walls.

2. A leer for glassware, comprising a horizontally disposed main annealing chamber having ascending and descending legs communicating with its opposite ends, said chamber having a substantial length and being located at a relatively great elevation whereby is created a natural seal for con-

fining heat thereto, the ascending leg having a charging opening therein adjacent to its lower end, an approximately horizontal cooling chamber communicating with said descending leg and leading forward therefrom, and an endless conveyor arranged for travel for carrying ware from the charging opening to and through said main annealing chamber and thence to and 10 through said cooling chamber.

3. In an annealing leir, a supporting frame, a horizontally disposed main annealing chamber carried by said frame at an elevation affording a clear floor space for workmen thereunder, vertical ascending and descending passages communicating with the opposite ends of said chamber, said ascending passage having a charging opening therein adjacent to its lower end, an approximately horizontal cooling chamber in 20 communication with the lower end portion of said descending passage, and an endless conveyor disposed for travel through said passages and chambers, said conveyor employing ware supports which are permanently maintained in horizontal carrying position.

4. A leir for glassware, comprising a main annealing chamber having ascending and

descending legs communicating with its opposite ends, said chamber being located at a relatively great elevation whereby is created a natural seal for confining heat thereto, the ascending leg having a charging opening therein adjacent to its lower end, an approximately horizontal cooling chamber communicating with said descending leg, a plurality of sets of sprocket wheels located adjacent to the angles between said chambers and said passages, the sprocket wheels of each set having a staggered arrangement, endless chains arranged for travel on said sprocket wheels for carrying ware from the charging opening to and through said main annealing chamber and thence to and through said cooling chamber, bars journaled on said chains with one end thereof in advance of the other, and ware-carrying trays mounted upon said bars, said bars being adapted to permanently support 50 said trays in horizontal position.

In testimony whereof, I affix my signature in presence of two subscribing witnesses.

DAVID STENHOUSE.
